UNITED STATES PATENT OFFICE.

SAMUEL JOSEPH HARTNELL, OF OSWEGO, OREGON.

TOY BASKET-BALL DEVICE.

No. 910,811.

Specification of Letters Patent.

Patented Jan. 26, 1909.

Application filed November 11, 1908. Serial No. 462,049.

To all whom it may concern:

Be it known that I, SAMUEL J. HARTNELL, a citizen of the United States, and a resident of Oswego, in the county of Clackamas and

5 State of Oregon, have invented a new and Improved Toy Basket-Ball Device, of which the following is a full, clear, and exact description.

The purpose of my invention is to provide 10 a novel, simple device which in use partakes of the character of the basket ball game, and is particularly well adapted for the amusement of young persons; the successful manipulation of the toy requiring dexterity and 15 skill, training the hand and eye, affording agreeable exercise, and also amusement to the players and those interested in the game.

The invention consists in the novel construction and combination of parts, as is 20 hereinafter described and defined in the appended claims.

Reference is to be had to the accompanying drawing and characters of reference thereon, the view shown being a perspective 25 illustration of the improved toy.

An elongated block A constitutes the main portion or body of the device, and as represented, is longitudinally and deeply channeled on the normally upper side thereof, 30 said channel a terminating at points a' near each end of the body A. At one end a handle B is formed or secured on the body A, affording means for the convenient manipulation of the complete toy.

35 At opposite points, preferably near the longitudinal center of the body A, two standards C, C, are secured thereon by their lower ends and extend vertically, having an equal length and other dimensions that are similar.

40 Between the standards C a gate D is pivoted, the pivots that are disposed oppositely near the upper edge of the gate, as shown for one pivot at b, permitting the gate to hang loosely between the standards and in the channel a.

45 A basket or like receptacle E, that is preferably hemispherical in shape, is secured by the edge of its open top between the upper ends of the standards C. There is a spherical ball F provided as a completing detail of

the device, and the method of operating the 50 toy involves the transfer of the ball past the gate D and from the channel a into the basket E.

The operator in preparing the device for a test of skill, grasps the handle B and places 55 the ball F in the channel a at a point near the handle. In order to give the ball the necessary impetus, the body A is tipped first toward the outer end, so as to roll the ball past the gate D, and then said ball is 60 returned by reversely inclining the body. When it is thought the ball has received proper endwise movement toward the outer extremity of the body A, a dexterous movement of the latter upward at said outer end 65 will toss the ball from the channel a upward and into the basket.

It will be noted that the operator must time the movement of the ball and force of impact it has upon the gate D, so that it 70 will arrive at the outer end of the channel a and be thence thrown upward by a combined inclining and tossing movement, that requires good judgment, a trained eye and dexterous manipulation for the successful 75 playing of the game of toss and catch with the improved toy basket ball device.

Having thus described my invention, I claim as new and desire to secure by Letters Patent:

1. A toy, embodying an elongated body having a longitudinal channel therein, a pair of standards, a gate pendent between the standards, and a receptacle on the standards. 80

2. A toy, embodying an elongated body having a longitudinal channel therein formed in the normally upper side, two standards erected oppositely on the body in parallel planes, a hemispherical basket secured between the standards at their upper ends, and 85 a gate pivoted between the standards and depending into the channel. 90

3. A toy, embodying an elongated body having a longitudinal channel in its upper side extending nearly the length of said body, 95 two standards of an equal height secured oppositely on the sides of the body near the center thereof, a flat gate pivoted near its

upper edge between the standards and depending into the channel, a hemispherical basket secured between the standards at their upper ends, and a spherical ball mov-
5 able in said channel.

4. A toy, embodying a channeled body, standards thereon, a gate pendent and rock-able between the standards, a basket secured between the upper ends of the standards,
10 and a ball that is rolled in the channel,

passes the gate, and is tossed into the basket by the manipulation of the body.

In testimony whereof I have signed my name to this specification in the presence of two subscribing witnesses.

SAMUEL JOSEPH HARTNELL.
